UNITED STATES PATENT OFFICE.

JOHN JOSEPH MOONEY, OF NEW ORLEANS, LOUISIANA.

DESIGN FOR A VENTILATOR-CAP.

SPECIFICATION forming part of Design No. 16,010, dated March 31, 1885.

Application filed September 20, 1884. Term of patent 14 years.

To all whom it may concern:

Be it known that I, JOHN J. MOONEY, a citizen of the United States, residing at New Orleans, in the parish of Orleans and State of Louisiana, have invented and produced a new and original Design for Ventilator-Caps, of which the following is a specification.

My design consists of a cylindrical base portion and a conical top portion having a plurality of dormer projections disposed around it, said projections being each in duplicate, one within the other.

It also consists in a peculiar ornamentation of the cylindrical portion, the conical portion, and the said dormer projections.

In order to clearly describe and make known my design, I have embodied it in a ventilator-cap, of which the accompanying drawing is a representation.

Referring to said drawing, A represents the conical portion of the cap, and B the cylindrical base portion.

C represents a series of gable-like or dormer projections arranged symmetrically about the cone A. They may be perforated, as shown at c'.

Within the projections C there is a second

series of similar but smaller projections, C', arranged to leave exposed the intermediate surface of the cone A, as at a.

The apex of the cone A may be terminated in any suitable manner by a vane, or by a spire and ball, as shown.

The ornamentation of the base B consists of a series of downwardly-projecting points, b, and a series of outwardly-projecting points, b'.

With the above-described cone and base I have combined what may be termed a "sub-base," D, ornamented around its circumference with a series of beads, d.

What I claim as my invention, and desire to secure by Letters Patent, is—

In a design for a ventilator-cap, a conical portion, A, having a series of dormer projections, a base, B, having an outwardly-extending fringe, b', and a sub-base, D, arranged within the base B, as set forth.

In testimony whereof I have hereunto set my hand, this 15th day of September, 1884, in the presence of two witnesses.

JOHN JOSEPH MOONEY.

Witnesses:
